Patented Oct. 7, 1902.

J. G. RIEL.

DEVICE FOR CLEARING FLUME GRATINGS.

(Application filed Mar. 26, 1902.)

(No Model.)

UNITED STATES PATENT OFFICE.

JOSEPH G. RIEL, OF MITTINEAGUE, MASSACHUSETTS.

DEVICE FOR CLEARING FLUME-GRATINGS.

SPECIFICATION forming part of Letters Patent No. 710,804, dated October 7, 1902.

Application filed March 26, 1902. Serial No. 100,021. (No model.)

To all whom it may concern:

Be it known that I, JOSEPH G. RIEL, a citizen of the United States of America, residing at Mittineague, in the county of Hampden 5 and State of Massachusetts, have invented new and useful Improvements in Devices for Clearing Flume-Gratings, of which the following is a specification.

This invention relates to devices for keeping the gratings which guard the entrance to a mill-race free from obstruction, whether the latter are in the form of floating ice or debris, and whereby the formation of anchor-ice on said grating is prevented, the object of the 15 invention being to produce a device of this character which may be applied to any grating already constructed; and the invention consists in the construction described in the following specification and pointed out in the 20 claim.

In the drawings forming part of this application, Figure 1 is a sectional side elevation of a mill-race or flume having the usual grating at the entrance thereof and showing 25 my invention applied thereto. Fig. 2 is a front elevation of Fig. 1, a portion thereof being broken away. Fig. 3 is a perspective view, somewhat enlarged, of a part of the grating and a part of my improved devices applied thereto.

Referring now to the drawings, *a* indicates the bars forming the usual grating over the entrance of a mill-race or flume which are set in a suitable frame of timbers, (indicated by *b*.)

To provide a support for the devices constituting my invention, I secure to the members *b* a rectangular frame consisting of the two uprights *c* and a suitable sill-piece *d*. To the inner edge of the uprights *c* there are 35 secured in any convenient way the strips *e*, provided with a channel therein and extending from end to end thereof for the reception of a sliding frame *f*, which is rectangular and is preferably made of metal and may slide 40 freely in a vertical plane, guided in its movements by the channel-strips *e*, in which the two vertical sides are entered. Extending horizontally from side to side of this frame *f* are bars *g*, rigidly held in said frame, and on 45 these bars are fingers *h*, so spaced that they will enter the spaces between the bars *a* of the grating, as shown in Fig. 3. The bars *g*

may be secured in the frame *f* and the fingers *h* secured thereto in any desirable way to hold the latter rigidly in the horizontal position and provide for the proper spacing thereof. A good method of securing the fingers to the bars *g* is shown in the drawings; and it consists in making the bars round, then planing off one side thereof, and casting 55 the fingers *h* with an opening through the hub corresponding in outline to the shape of the bars *g* in cross-section. The fingers *h* may then be slipped onto the bars, with suitable washers *i* between them, whereby the 60 proper spacing may be obtained. This construction permits one by simply varying the width of the washers to space the fingers to correspond to the spacing of any grating-bars *a*. Preferably two of the bars 65 *g* are applied to the frame *f*, so located that the entire submerged length of the bar *a* may be traversed by the fingers *h* during the 70 vertical reciprocatory movements of said frame. To provide for this movement of the 75 frame *f*, at the upper edge thereof there are provided two short arms *j* for receiving the horizontal shaft *k*, from each end of which a connecting-bar *m* extends upwardly to the 80 side of a gear *n*, to which it is pivotally attached eccentrically thereto, said gears being of such diameter that their rotation will provide for the requisite reciprocatory movement 85 of the frame, the gears being supported on a shaft *o*, hung in proper bearings *p* on the upper end of the uprights *c*, all as shown. Parallel with the shaft *o* is a second shaft *q*, also supported on the uprights *c* in bearings *r*, having thereon pinions *s* in mesh with the 90 gears *n*, and on one end of said shaft *q* means are provided for driving it—as, for example, the beveled gear *t*, adapted to be engaged by another gear on a shaft running to some suitable source of power.

To facilitate and render more uniform the 95 movements of the frame *f*, I provide for the latter suitable counterweights *u*, hung on a chain *v*, whose opposite end is attached to the top of the frame. These chains run over grooved pulleys *w*, supported in bearings *x*, 100 bolted to the uprights *c*.

From the foregoing description it is seen that the device may be applied to any flume-grating in front of which the uprights *c* may

be secured and that by means of their regular reciprocating vertical movements the fingers *h* will dislodge anything which may become attached to the grating-bars *a*, said fingers having sufficient rigidity to shear off ice that may form thereon or to dislodge sticks or other floating debris that may be carried against the grating by the flow of water therethrough.

10 Having thus described my invention, what I claim, and desire to secure by Letters Patent of the United States, is—
The combination with the grating of a mill-

race, of a vertically-reciprocating frame supported in parallelism therewith, channeled 15 guide-strips for said frame, bars extending from side to side of said frame, fingers on said bars extending horizontally between the bars of said grating, a counterweight for said frame, a wheel and a pitman connection between said wheel and said frame, and means for rotating said wheel.

JOSEPH G. RIEL.
